[57] CLAIM

The ornamental design of a temperature and humidity measuring device, as shown and described.

DESCRIPTION

FIG. 1 is a front elevational view of a temperature and humidity measuring device showing my new design in the inoperative condition;

FIG. 2 is a front elevational view thereof in the operative condition showing a typical digital display;

FIG. 3 is a rear elevational view thereof;

FIG. 4 is a left side elevational view thereof;

FIG. 5 is a right side elevational view thereof;

FIG. 6 is a cross-sectional view thereof as taken from line A—A of FIG. 1;

FIG. 7 is a top plan view thereof;

FIG. 8 is a bottom plan view thereof;

FIG. 9 is a cross-sectional view thereof as taken from line B—B of FIG. 1.

FIG. 3

FIG. 2

FIG. 1

FIG. 6

FIG. 5

FIG. 4

FIG. 9

FIG. 7

FIG. 8
